22

A technical drawing showing a cross-section of a specimen. The top left corner is labeled '33'. The bottom left corner is labeled '17'. The bottom center is labeled '28'. The bottom right corner is labeled '34'. The bottom right corner is also labeled '31'. The bottom right corner is also labeled '15'. There are several diagonal and horizontal lines indicating the dimensions and features of the specimen.

Fig. 10

A technical line drawing of a mechanical component, possibly a housing or a bracket. The drawing shows a central vertical slot with a semi-circular cutout at the bottom. To the left of this slot, there is a vertical section labeled '15' at the bottom and '36' above it. To the right of the slot, there is a vertical section labeled '38' at the top and '17' below it. Above the slot, the numbers '37' and '30' are positioned. To the right of the main assembly, a vertical scale is shown with the number '10' at the top. The entire drawing is enclosed in a rectangular border.

UNITED STATES PATENT OFFICE.

FRANZ JULIUS CARL AND HERMANN GUSTAV CARL, OF CHICAGO,
ILLINOIS.

WINDOW.

SPECIFICATION forming part of Letters Patent No. 741,457, dated October 13, 1903.

Application filed December 3, 1902. Serial No. 133,800. (No model.)

To all whom it may concern:

Be it known that we, FRANZ JULIUS CARL, a citizen of the United States, and HERMANN GUSTAV CARL, a subject of the Emperor of 5 Germany, both residing in the city of Chicago, in the county of Cook and State of Illinois, have invented a new and useful Improvement in Windows, of which the following is a specification.

10 This invention relates to the manner of hanging window-sashes in dwellings and other buildings; and our object therein has been to provide a practical construction whereby both the upper and lower sashes of the ordinary 15 vertically-movable type may be also capable of swinging, and thus be rendered accessible for cleaning the glass upon both its inner and its outer sides without the use of step-ladders and without reaching out of the window or 20 otherwise gaining access to the glass from the outside of the building, as is requisite with the ordinary vertically-sliding sashes.

The nature of our improvement is fully set forth below and will be understood from the 25 description thereof when considered in connection with the drawings, in which—

Figure 1 is an elevation of a window embodying our invention. Fig. 2 is a section thereof on the line 2 2 of Fig. 1. Fig. 3 is a 30 horizontal section on the line 3 3 of Fig. 1. Fig. 4 is a horizontal section showing a double window with the sashes all swung open. Fig. 5 is a section on the line 5 5 of Fig. 1. Fig. 6 is a section on line 6 6 of Fig. 1. Fig. 35 7 is a partial elevation of one of the sashes. Figs. 8, 9, 10, and 11 are detail views of the hinges. Fig. 12 is a detail section of one of the antifriction-rollers.

In the drawings, 15 represents the window-frame, and 16 is the upper sash, and 17 the lower sash. Both are provided with counter-balance-weights, that of the upper sash being shown at 18 and that of the lower one at 19, the cords 50 passing over pulleys 20. But 40 one weight is used with either sash in order that one side of each may be free to swing open without detaching any sash-cord. Each sash is also provided on one side with hinging devices, as indicated. In the case of the 45 50 upper sash sockets or eyes 21 and 22, each formed on the ends of straps 23 and 24, are

secured, respectively, to the top rail and the meeting-rail, as seen more particularly at Fig. 7, and the window-frame is provided with a pivot 25 near the center of the side rail of 55 the frame adapted to enter said socket 21 when the sash is lowered to its lowermost position, and a second pivot 51 near the bottom adapted to enter the socket 22 when the upper sash is in its lowest position. This construction permits the lowering of the sash and its being swung open while in the lowered position.

In the case of the lower sash sockets or eyes 27 and 28 are attached near the top and bottom, respectively, of one of the side rails of the sash, and the side of the window-frame is provided with corresponding pivots 29 and 30, each adapted to enter one of said sockets when the sash is in its normal plane and to 65 permit it to swing upon them. The upper socket is adapted to set down over the pivot 29; but the socket 28 is fashioned differently, having an open slot 31 formed in its side and extending from top to bottom in order that 70 when the sash is raised the socket 28 may pass entirely by pivot 29 without interference, the slot giving room for the leaf 32, supporting the pivot, as one moves past the other, as 75 will be understood from Fig. 6. 80

Upon the hinged side each sash is formed with an ogee curve, (seen at 33 in Figs. 3 and 4,) with an overlapping shoulder 34, and the side of the frame is correspondingly shaped. This form permits all necessary swinging of 85 the sash, forms a tight joint with the sash when the latter is closed, and holds the sash firmly against pressure from without. The weights and the hinges of each sash are located on the same side thereof, as the sash-cords 90 supporting the weights freely permit all necessary torsion caused by the swinging of the sash.

Guide-rollers 36, of which one is provided upon each sash, project from the sash into 95 guide-slots 37, formed in the window-frame opposite them, the inner wall of the slots being cut away at one point, as at 38, to permit the roller to move out of the slot when the sash is to be swung open. The rollers lock 100 the sashes when they are out of the swinging plane and also relieve the increased friction

caused by the use of a single weight instead of the two commonly used, as they are located near the upper corners of the sashes, where the friction is greatest.

5 The sashes may be locked together in the usual way by a sash-fastener 39, located centrally of the meeting-rails; but instead of relying upon the fastener as a means of locking the sash bolts or catches 40, operated by 10 the key or handle 41, may be applied to one or both sashes, the one applied to the upper sash being sunk into the wood, so as not to interfere with the sliding of the lower sash. The sill of the window is desirably hollowed out, 15 as at 42, to catch any rain which may find its way through the window. The upper rail of the upper sash and the lower rail of the lower sash are both fashioned, as plainly shown in Fig. 2, in order that they may effectually exclude both cold and rain.

It will be noticed that the hinges of each sash are at the same side with its weight, so that we not only avoid any necessity of detaching the sash-cord when the sash is swung 25 open, but avail of the flexibility of the cord, which permits the swinging. It will also be noticed that the weight and hinges of each sash are upon a different side from the weight and hinges of the other sash, so that there 30 need be no interference between them when swung open. The hinges used are all separable and are united and separated by the vertical movements of the sash, as will be understood from the description already given.

35 With the construction described the sashes are permitted to slide up and down with the same freedom as the ordinary sash, the lower sash can be swung inward without any preparatory change of position, and the upper 40 sash can also be swung inward by first lowering it, so its hinge-sockets effect operative relations with pivots 25 and 51.

The invention may also be applied to double windows, and I show at Fig. 4 a section of 45 such a window with all the sashes swung open. In the double window both the inner and outer windows correspond in construction and manner of hanging with the construction above set forth.

50 We claim—

1. The combination in a window of upper

and lower sashes, both adapted to slide vertically and to swing inward from opposite sides when in their lower positions, and both provided with separable hinges, the parts of 55 which are assembled when the sashes are in their lower positions.

2. The combination in a window of upper and lower sashes, both adapted to slide vertically and to swing inward from opposite sides 60 when in their lower positions, and both supported by weights attached to them on their hinged sides only, the hinges upon which the sash swing being separable.

3. The combination in a window, of upper 65 and lower sliding sashes, each supported at one side only by a sash-weight and each having an antifriction-roller at its unsupported side bearing on the window-frame, and the weight and the roller of one sash being at the 70 opposite side of the window from the weight and roller of the other sash, substantially as specified.

4. The combination in a window, of upper and lower sliding sashes, each supported at 75 one side only by a sash-weight and provided with hinges at its supported side upon which it may swing when in its lowest position, and each also provided with the antifriction-roller at its unsupported side entering a groove in 80 the window-frame, substantially as specified.

5. The window having upper and lower sash which slide and also swing inward on separable hinges when in their lower positions, the socket of one of the hinges being slotted to 85 enable it to pass the stationary pivot of another hinge, substantially as specified.

6. The combination in a window of an upper sash and a lower sash both sliding vertically, and both swinging on separable hinges when 90 in their lower positions, the hinges of the upper sash being normally separated and those of the lower sash being normally complete, and its hinges being located at the opposite side of the window from the hinges of the upper 95 sash, substantially as specified.

FRANZ JULIUS CARL.
HERMANN GUSTAV CARL.
